[57] CLAIM

The ornamental design for a belt mounted accessory bag or the like, substantially as shown and described.

DESCRIPTION

FIG. 1 is a top plan view of a belt mounted accessory
bag or the like showing my new design;
FIG. 2 is a front elevational view thereof;
FIG. 3 is a side elevational view, the opposite side not shown being a mirror image thereof, FIG. 4 is a rear elevational view thereof; and
FIG. 5 is a bottom plan view thereof.
The broken lines on the flap and loops of the bag indicate stitching.
